UNITED STATES PATENT OFFICE.

JOSEPH LEVIN, OF BALTIMORE, MARYLAND.

PARASOL.

1,342,451.

Specification of Letters Patent.

Patented June 8, 1920.

Application filed August 19, 1919. Serial No. 318,491.

To all whom it may concern:

Be it known that I, JOSEPH LEVIN, a citizen of the United States of America, residing at Baltimore, State of Maryland, have 5 invented certain new and useful Improvements in Parasols, of which the following is a specification.

The primary object of the present invention resides in the provision of a parasol of 10 the folding type that is adapted to be collapsed when out of use and folded substantially to assume the shape and formation of a lady's hand bag or like receptacle for more conveniently carrying the same.

15 The particular details of the invention relate to novel improvements offering an advance in the art over a prior patent granted to me on July 15, 1919, No. 1,310,399, the specific improvements including a ring or 20 annular member associated with the tip end of the parasol stick for causing the parasol when collapsed or folded to assume the shape of a circular bag, as distinguished from a flat bag disclosed in said patent.

25 A still further improvement includes the positioning of the hand grips or carrying cords inwardly of the peripheral edges of the parasol cover so that when the parasol is unfolded and in use, the hand grips are 30 hidden from view.

With the above general objects in view and others that will appear as the nature of the invention is more fully understood, the device consists in the novel construction, 35 combination and arrangement of parts to be hereinafter more fully described and then claimed, reference being had to the accompanying drawings by like characters designating corresponding parts throughout the 40 several views, wherein,

Figure 1 is a bottom plan view of a parasol constructed in accordance with the present invention and open for use, the stick being shown in section, illustrating the hand 45 grips or cords positioned at points spaced inwardly from the edges of the parasol cover,

Fig. 2 is a cross sectional view taken centrally through Fig. 1,

50 Fig. 3 is a side elevational view of the parasol in collapsed and folded position showing carrying cords therefor,

Fig. 4 is a side elevational view of the parasol frame with the cover and ribs removed and with the handle folded,

55 Fig. 5 is a side elevational view of the

umbrella frame on an enlarged scale similar to the illustration in Fig. 4 with the ring member shown in section and a portion of the cover attached thereto, and

60

Fig. 6 is a top plan view of the ring member carried by the outer end of the parasol stick, the same being partially shown in section to illustrate the manner of attaching the rib thereto.

65

Briefly described, the present invention aims to provide a parasol of the folding type in which the parasol when distended and ready for use will present a rigid appearance and will be practically so constructed

70

while the parasol when folded assumes a cylindrical shape in the form of a bag with carrying cords connected at their ends to the parasol ribs intermediate the ends thereof, normally lying within the outer plane 75 of the parasol. This circular formation when the parasol is folded is accomplished through the medium of a ring or annular member secured to the outer end of the parasol stick with the ribs of the parasol pivoted 80 to said ring thus presenting a substantially flat bottom portion simulating a bag when the parasol is folded with the handle adjustable relative to the stick and positioned within the sides of the parasol cover. It is 85

to be noted that the cover of the parasol constitutes the cover of the bag, and an additional member acting as a cover is not required. While it is not intended to restrict the invention to the material from which 90 the cover is to be made it is especially desired that a flowered material such as cretonne or brocaded silks be employed so that in addition to presenting a parasol possessing beauty, the parasol when folded into the 95 form of a bag will prove to be exceptionally attractive.

Referring more in detail to the construction of the device and particularly to Figs. 2, 4, 5 and 6 there is illustrated an umbrella 100 stick 7 having a link connection 8 with a tubular handle 9, the handle being foldable as illustrated and adapted for rigid alignment relative to the stick 7 by engaging the threaded portion 8' of the link construction. 105 A novel feature of the present invention resides in the provision of a ring member embodying a central hub 10, carrying spiders 11 to the outer ends of which the U-shaped ring 12 is connected, the hub, spider 110 and ring preferably being integrally formed with the ring positioned substantially in

alinement with the outer end of the hub 10 while brace rods 13 extend between said ring and the inner end of the hub as clearly illustrated in said figures.

5 A runner 14 is slidably mounted upon the stick 7 and coöperates with tensioned catches 15 and 16 and is provided with the usual grooved annular enlargement 17 into which grooves the inner ends of the stretch-
10 ers 18 are pivoted, the outer ends of the stretchers being pivoted as at 19 to the ribs 20 at points intermediate the ends thereof, the inner ends of the ribs being received into notches 21 provided in the upper and
15 lower edges of the U-shaped ring 12 while a binding wire 22 seated in the bight of said ring passes through openings in the inner ends of said ribs as clearly illustrated in Figs. 5 and 6.

20 The covering of the frame work above described includes a protecting sheet 23 suitably secured to the outer face of the ring 12 and extending completely over the same as illustrated in Fig. 5 while the
25 parasol cover proper, 24 is suitably secured to the ring and extends over the rib construction to be secured to the tips 20' of the ribs in any preferred manner.

30 From the description heretofore given the construction and operation of the parasol is believed to be clearly apparent, it being noted that Figs. 1 and 2 illustrate the parasol as being distended with the runner 14 engaged by the catch 15 and when so ar-
35 ranged it will be observed from an inspection of Figs. 2 and 5 that the stick 7 terminates inwardly of the outer plane of the ring 12 so that an uninterrupted flat upper surface is presented to the exclusion of a
40 projecting stick.

45 When it is desired to carry the umbrella in the folded position shown in Fig. 3 in simulation of a hand bag or like device, the runner 14 is released from the catch 15 and moved to engagement with the catch 16, during which movement the ribs 20 are moved into closer relationship with the stick 7 by the pivotal connections with the wire 22 and when so arranged the handle 9 is
50 disengaged from the stick 7 and folded par-
allel therewith as indicated in Fig. 5 with the cover of the parasol bending upon the outer face of the ring 12 to inclose the stick and handle completely to hide the same
55 from view thus presenting a bag formation having a flat bottom free of projections and cylindrical side walls.

60 As illustrated in Fig. 1 hand cords 25 are connected at their ends to ribs 20 at points spaced inwardly of the tips 20' thereof, a pair of hand cords being diametrically ar-
65 ranged so that when the parasol is in open position as shown in Fig. 1 the same are spaced inwardly of the edge of the parasol to be hidden from view, but which, when

the parasol is folded into bag formation as illustrated in Fig. 3 functions as a carrying element. It will be seen that there is provided an improved form of foldable parasol which will perform all of the duties of an ordinary rigid construction of parasol, but still be capable of folding into the formation of a lady's hand bag for easily and more conveniently carrying the same.

70 While there is shown and described the preferred embodiment of the invention, it is to be understood that various changes may be made in the detail of construction which will fall within the scope of the invention as claimed.

75 What is claimed as new is:—

1. In a parasol, the combination with a stick, of a ring carried by the outer end of the stick, ribs pivoted to said ring, a cover attached to the ribs, the cover and ribs when folded presenting a flat bottom with the pivoted ends of the ribs spaced at all times, and means arranged diametrically of the cover for carrying the parasol when collapsed.

80 2. In a parasol, the combination with a stick, of a ring carried by the outer end of the stick, ribs pivoted to said ring, a cover attached to the ribs, the cover and ribs when folded presenting a flat bottom with the pivoted ends of the ribs spaced at all times, and means arranged diametrically of the cover for carrying the parasol when collapsed, said means including hand cords connected to ribs at points spaced inwardly of the tips thereof whereby said cords are hidden from view when the parasol is opened.

85 3. In a parasol, the combination with a stick, of an annular member secured to the outer end of said stick, ribs pivoted to the annular member in circular formation and spaced from the outer end of the stick, a cover secured to said ribs and ring, a handle pivoted to said stick, the ribs when folded inclosing the stick and handle, and hand cords secured diametrically of the cover at points spaced inwardly of the edges thereof constituting carrying means for the parasol when folded.

90 4. A parasol comprising a stick, ribs pivoted relative thereto, a cover for said ribs, means associated with said stick for pivotally supporting said ribs adapted to cause the parasol to assume a flat bottom and substantially cylindrical side walls when the ribs are folded, said means including a central hub portion secured to the stick, spiders radiating from said hub, a ring carried by the outer ends of said spiders to which the ribs are pivoted and braces between said hub and ring.

95 5. A parasol comprising a breakable stick, ribs pivoted relative thereto, a covering for said ribs, hand cords normally positioned

90

130

within the periphery of the cover, and means associated with said stick and ribs to cause the parasol when folded to present a flat bottom free of projections and substantially cylindrical side walls inclosing the stick, the hand cords constituting carrying members for the parasol when folded.

5. A device of the class described comprising a stick, a collapsible canopy carried thereby, said canopy assuming the appearance and form of the body of a lady's hand bag and substantially entirely inclosing the stick when collapsed, and opposite carrying members carried by the canopy and adjacently positionable externally of the canopy when the canopy is collapsed whereby the device may be carried similar to a lady's hand bag.

10. A device of the class described comprising a stick, a collapsible canopy carried thereby, said canopy assuming the appearance and form of the body of a lady's hand bag and substantially entirely inclosing the stick when collapsed, opposite carrying

members carried by the canopy and adjacently positionable externally of the canopy when the canopy is collapsed whereby the device may be carried similar to a lady's hand bag, said carrying members being arranged so that the same are hidden from view when the canopy is expanded.

15. A device of the class described comprising a stick, a collapsible canopy carried thereby and including pivoted ribs, said canopy including means to cause the same to present a bottom relatively large as compared to the length of the canopy when collapsed and said means allowing the ribs to fold inwardly sufficiently to provide substantially cylindrical side walls for the canopy whereby the latter may assume the appearance and form of the body of a lady's hand bag when collapsed, and carrying means for permitting the device to be carried similar to a lady's hand bag.

20. In testimony whereof I affix my signautre.

JOSEPH LEVIN.
